Patented Dec. 19, 1916.

UNITED STATES PATENT OFFICE.

LUDWIG WOLFFGRAM, OF BROOKLYN, NEW YORK.

MAKING LONG SEAMLESS THIN-ROLLED TUBES OUT OF WARM SOLID BLOCKS OF METAL.

1,208,876.

Specification of Letters Patent. Patented Dec. 19, 1916.

Application filed June 16, 1915. Serial No. 34,367.

To all whom it may concern:

Be it known that I, LUDWIG WOLFFGRAM, a citizen of the German Empire, and a resident of New York, in the borough of Brooklyn, county of Kings, and State of New York, have invented certain new and useful Improvements in Making Long Seamless Thin-Rolled Tubes Out of Warm Solid Blocks of Metal, of which the following is 10 a specification.

This invention relates to improvements in making long seamless thin rolled tubes out of warm solid blocks of metal. Heretofore, such tubes were made with the use 15 of a long rod having at its end a guided mandrel and supported by guide blocks arranged within an outer casing, which guide blocks were pushed along the interior of the casing by the tube as it was gradually 20 formed from the block passing over the mandrel. On the completion of the tube formation, these guide blocks were pushed out of the casing at its end distant from the mandrel end of the rod, and while 25 rounding the rod and supported thereby, were removed therefrom. On the entire completion of the tube, and its extraction from the casing, the guide blocks were again inserted into the casing to proper 30 position in the casing to be in working position for the next tube formation. This system had several disadvantages. Among these was that the rod within the casing could not be conveniently cooled as it became heated. Another was that the guide 35 blocks were inconvenient in manipulation, and another was that during the formation the services of the workmen were not efficiently utilized, in that they could not do 40 anything until the tube was completed, while thereafter the positioning of the guide blocks was wasteful in time, with consequent expense in operation.

My improvement overcomes these disadvantageous features, and by providing independently operating guide blocks formed of two parts so as to be readily removed or placed in position, the outer casing is done away with, and a cooling of the rod is readily made possible, as also time is saved, and at the same time the services of the workmen can be utilized during the forming of the tubes.

My invention is shown in the accompanying drawings and will be more fully de-

scribed hereinafter and finally pointed out in the claims.

In the drawings, Figure 1 is a side view of the mechanism used in carrying out my invention, Fig. 2 is a front view thereof, 60 Fig. 3 shows a modified form of guide block, Fig. 4 shows still another form of guide block, Fig. 5 represents a longitudinal section of the adjustable holding mechanism for one end of the mandrel, and Fig. 6 represents a top plan view thereof.

Similar reference numerals indicate corresponding parts throughout the several figures of the drawing.

Referring to the drawings, the base 10 has standards 11, each supporting a table 12, on which the guide blocks 13 are movable. The rod 14 has the mandrel 15, as is well known, and the position of the rod 14 is regulated by the mechanism 16. This 70 mechanism comprises a cylindrical casing 39 (see Fig. 5 especially), a piston 40 movable horizontally in said casing by means of a threaded spindle 42 extending through the head of the casing and provided with 80 an exterior hand-wheel 41. A spindle 43 is supported on ball bearings in said piston. This spindle extends through the opposite end of said casing and is provided with an exterior head 44 having an angular socket 85 adapted to be engaged by the angular terminal of the rolling bar 14. Rotary motion is imparted to the rolling bar 14 by a seamless tube blank which engages the mandrel 15 at the outer end thereof, said blank being 90 rotated by the action of the three forming rollers in the usual manner. Each of the guide blocks 13 is composed of two parts 17 and 18, hinged at 19, and having projections 20 and 21 for engaging corresponding 95 guides 22 and 23, suitably arranged on the tables 12 or alongside thereof for the purpose of guiding the guide blocks 13. The guide blocks are arranged in two parts pivoted to each other to be readily openable.

As is well known, the mandrel 15 is properly positioned with nicety, to carry out the object for which it is intended to be used, co-operating in the usual manner with three 105 forming rolls, not shown. Simultaneously therewith, the guide blocks 13, either two or as many as are desired, are placed in position. As the tube is formed, the tube moves the guide blocks as heretofore, but 110

instead of moving the first guide block along the inside of the entire casing, the first guide block is only moved to the end of the first table. When it has reached the end of this 6 table, the guide block, having passed out of the guide grooves, falls to the ground, opening either automatically or under manual operation, the openable feature thereof permitting this. The guide-block having passed 10 out of the guide grooves may, as stated, fall either to the ground, or be in a position on the rod where it may be readily removable either by hand or automatically, from the rod, without falling on the ground. There- 15 upon, the end of the drawn tube moves farther along until it encounters the next guide block, whereupon the same operation takes place, and so on. As these guide blocks fall from the rod 14 to the floor, the workmen 20 pick them up, and get them into shape for the next tube forming, placing them in a handy place within convenient reach. The rod 14 being exposed may be conveniently cooled by jets of water without interference 25 with the progress of the work. The advantage therefore is that a two-part guide block is used directly at those parts where it ought to be, whereas in the old form, the guide blocks had to be pushed to these places. 30 Furthermore, by keeping the rod at all times in position and cooling the same, an appreciably higher effectiveness results, and better quality of tubes is obtained.

In Fig. 3 is shown a different form of 35 guide block, in which the pivot 30 connects two members 31 and 32, the angular parts 33 and 34 of which engage stationary guides 35 and 36, while Fig. 4 shows a circular ex-

terior 37 engaging stationary circular guides 38.

The invention is applicable to the three rollers of the Mannesmann process, and also to the other processes, as for instance, the Stiefel process in which two conical rollers are used. Of course, the invention is applicable to any other methods, and I have shown several embodiments, but it is clear that changes may be made therein without departing from the spirit of my invention.

Having thus described my invention, I 50 claim as new and desire to secure by Letters Patent —

1. In a tube rolling mill the combination 55 of guideways, guideblocks composed of separable sections adapted to traverse said guideways, and a rolling mandrel bar engaging said guideblocks, said blocks being adapted to be engaged and pushed by the tube being rolled and being free to drop off said bar when passing off the ends of said guideways.

2. In a tube rolling mill the combination 60 of guideways, guideblocks composed of hinged separable sections adapted to traverse said guideways, and a rolling mandrel bar engaging said guideblocks, said blocks being 65 adapted to be engaged and pushed by the tube being rolled and being free to drop off said bar when passing off the ends of said guideways.

In testimony that I claim the foregoing 70 as my invention, I have signed my name in presence of two subscribing witnesses.

LUDWIG WOLFGANG
